(57) **CLAIM**

The ornamental design for a shoe sole, as shown and described.

DESCRIPTION

FIG. 1 is a perspective view of a shoe sole in accordance with the new design, the dashed lines illustrating an upper of a shoe, which is not claimed and shown only to place the shoe sole in its typical environment;

FIG. 2 is a front view of the shoe sole illustrated in FIG. 1, the dashed lines illustrating an upper of a shoe, which is not claimed and shown only to place the shoe sole in its typical environment;

FIG. 3 is a rear view of the shoe sole illustrated in FIGS. 1 and 2, the dashed lines illustrating an upper of a shoe, which is not claimed and shown only to place the shoe sole in its typical environment;

FIG. 4 is a left side view of the shoe sole illustrated in FIGS. 1-3, the dashed lines illustrating an upper of a shoe, which is not claimed and shown only to place the shoe sole in its typical environment;

FIG. 5 is a right side view of the shoe sole illustrated in FIGS. 1-4, the dashed lines illustrating an upper of a shoe, which is not claimed and shown only to place the shoe sole in its typical environment;

FIG. 6 is a bottom plan view of the shoe sole illustrated in FIGS. 1-5, the dashed lines illustrating an upper of a shoe, which is not claimed and shown only to place the shoe sole in its typical environment; and,

FIG. 7 is a top plan view of the shoe sole illustrated in FIGS. 1-6, the dashed lines illustrating an upper of a shoe, which is not claimed and shown only to place the shoe sole in its typical environment, and wherein the dotted lines illustrate general curvature of the top surface of the sole, which is hidden from view during use and is not claimed herein.

1 Claim, 3 Drawing Sheets
